UNITED STATES PATENT OFFICE.

STEPHEN H. SIMSARIAN, OF WEST HOBOKEN, NEW JERSEY.

CIGAR-TIP CUTTER.

1,096,274.

Specification of Letters Patent. Patented May 12, 1914.

Application filed March 12, 1913. Serial No. 753,771.

To all whom it may concern:

Be it known that I, STEPHEN H. SIMSARIAN, a citizen of the United States, residing in the town of West Hoboken, in the county 5 of Hudson and State of New Jersey, have invented certain new and useful Improvements in Cigar-Tip Cutters, of which the following is a specification.

My invention relates to a class of new and 10 useful improvements in cigar tip cutters specially designed as personal ornaments or watch charms whereby the mechanism, when not in use, is completely concealed and the purpose of the article unapparent.

15 The objects of my improvements are attained by the mechanism illustrated in the accompanying drawing in which—

Figure 1 is a side elevation of the casing, housing the mechanism. Fig. 2 is a cross- 20 section flatwise of the casing having the mechanism in position with one of the spring-retaining-tongues removed. Fig. 3 is a transverse section through the narrow side 25 of the casing with the spring-retaining- tongues in position, which prevent complete withdrawal of the mechanism therefrom by their action against the involuted margin of the casing. Fig. 4 is a side view of one of the scissor-blades removed.

30 A represents a hollow shell or casing having two annular internal communicating compartments of varying size through the larger of which a segmental opening with involuted margins 7 is provided for entry 35 and withdrawal of the blades. The smaller compartment serves to house the mechanism, when closed or not in use, and has integral therewith the ring 8 for attachment to a watch chain or any other suitable suspen- 40 sion.

The interchangeable blades 1 and 2, Figs. 2 and 4, are pivotally connected after the fashion of scissors, having beveled semi-circular cutting faces *b b'* conveniently 45 placed between the finger tips *a a'* and their pivotal connection or fulcrum at 5, so that when the blades are withdrawn from the casing and extended by the U-shaped band spring 4, Fig. 2, secured in slot 6 on the 50 outer sides thereof, as shown, an opening is provided, through which a cigar tip is entered and snipped off by compression of the blades.

As referred to, the opening in the casing 55 A, Figs. 2 and 3, through which the scissor-blades are withdrawn has an involuted mar-

gin 7, forming a rod-like ridge, against which two spring-retaining-tongues 3, 3, with everted free ends being attached on each side of the blades at the pivot 5, strike 60 and prevent complete withdrawal of the mechanism from the casing; or when entered therein, stabilize the pivotal end of said blades, thus avoiding lateral motion, since the mechanism herein described is otherwise 65 loosely housed within the casing, where it is retained by the action of the U-shaped spring 4 in passing the constricted portion thereof.

The scissor blades 1 and 2, Fig. 2, are provided with finger tips *a a'*, by which they are manipulated, either in withdrawal from the casing or in snipping the cigar tip, as stated; and are so designed that, when the blades are entered, the opening in the cas- 75 ing A is completely concealed from view.

Having thus described the operation and mechanism of my invention, I claim—

1. A cigar tip cutter, comprising a hollow irregular casing, having an opening therein 80 with involuted margins, a pair of scissor blades with beveled semi-circular cutting faces, superimposed upon each other, pivoted together and slidably mounted in the casing, finger tips firmly attached to manip- 85 ulate the blades, a U-shaped band spring secured to and operably connected with each of the blades, said spring being adapted to pass through and abut upon either side of the constriction in the casing and two spring 90 retaining tongues laterally attached at the pivot of the blades and having their free ends everted against the sides of the casing to stabilize the blades.

2. A cigar tip cutter having a pair of 95 scissor-blades with beveled cutting faces, pivoted together and slidably mounted in a casing of two annular communicating compartments of varying size, a U-shaped expanding band spring attached outwardly to 100 the blades between their pivotal connection and the finger tips and two spring retaining tongues with everted free ends secured on opposite sides of the blades, all entered and housed in said casing.

3. The combination in cigar tip cutters having a casing, an opening in the casing with involuted margins, a pair of cigar tip cutting blades pivoted together and slidably mounted in the casing, finger tips firmly at- 105 tached to the blades, an expanding band spring holding the blades in open position 110

and housed within said casing by coaction against the constriction thereof and spring-retaining tongues, secured on opposite sides of said blades, with their everted free ends 5 engaging the involuted margins of the opening of the casing to prevent complete withdrawal of the blades in operation from said casing.

Signed at West Hoboken in the county of Hudson and State of New Jersey this tenth day of March, A. D. 1913.

STEPHEN H. SIMSARIAN.
